FIG. 1.

FIG. 2. INVENTOR Sigmund A. Dulczewski,
by his attorney
J. Edward Thebaud.

UNITED STATES PATENT OFFICE.

SIGMUND A. DULCZEWSKI, OF BUFFALO, NEW YORK.

DESIGN FOR A CLOCK-CASE.

55,120.

Specification for Design.

Patented May 11, 1920.

Application filed January 7, 1919. Serial No. 270,085. Term of patent 14 years.

To all whom it may concern:

Be it known that I, SIGMUND A. DULCZEWSKI, a citizen of the United States, residing at Buffalo, in the county of Erie and State of New York, have invented a new, original, and ornamental Design for a Clock-Case, of which the following is a specification, reference being had to the accompanying drawings, forming part thereof.

Figure 1 is a front elevation of a clock frame showing my design as it appears in relief.

Fig. 2 is a bottom plan of the base of said frame.

I claim:

The ornamental design of a clock case as shown.

SIGMUND A. DULCZEWSKI.
